UNITED STATES PATENT OFFICE.

OTTO LAUBER AND FRIEDRICH STOCK, OF ESSEN-ON-THE-RUHR, GERMANY, ASSIGNORS TO FRIED. KRUPP AKTIENGESELLSCHAFT, OF ESSEN-ON-THE-RUHR, GERMANY.

ELEVATING AND SIGHTING ATTACHMENT FOR GUNS.

No. 809,818.

Specification of Letters Patent.

Patented Jan. 9, 1906.

Application filed March 27, 1905. Serial No. 252,365.

To all whom it may concern:

Be it known that we, OTTO LAUBER and FRIEDRICH STOCK, subjects of the German Emperor, residing at Essen-on-the-Ruhr, Germany, have invented a certain new and useful Elevating and Sighting Attachment for Guns, of which the following is a specification.

The present invention relates to recoil-guns, and is especially applicable to field-guns in which the sighting device and mechanism for operating the same are arranged on the cradle and in which the angle of elevation of the gun-barrel is fixed by means of a screw elevating mechanism.

The object of the invention is to provide for an independent sight-line in such guns without essential alteration of the sighting device.

The invention is illustrated in the accompanying drawings, in which—

Figure 1 is a side elevation, on a scale smaller than that of the remaining figures, showing those parts of a gun having relation to the present invention. Fig. 2 shows a portion of Fig. 1, partly in section. Fig. 3 is a rear view of Fig. 2, partly in section, on line 3 3 of said figure and seen at a right angle to the section-plane. Fig. 4 is a sectional view on the line 4 4, Fig. 3; and Fig. 5 is a sectional view on the line 5 5, Fig. 3.

The cradle A, that carries the gun-barrel B, is supported by horizontal trunnions a', Fig. 1, on the mount C. To the cradle A are secured the carrier a'', Figs. 1 and 3, for the front sight a''' and the guide-piece a'' for the rear sight-post D, which carries a sight-telescope d' and a notch-sight d'', Fig. 3. The guide-piece a'' and the sight-post D are curved, as usual, in an arc concentric with the point of the front sight. The rear side of the sight-post is provided with a distance-scale d''', Fig. 3, and with teeth d''', Figs. 2 and 3.

The mechanism for fixing the angle of elevation of the gun preferably comprises two devices. The first elevating device consists of a hand-wheel e', a shaft E, a pair of cone-wheels e'' f'', an externally-threaded hollow screw-spindle F, and an externally and internally threaded hollow spindle G, the object of this first elevating device being to impart to the gun-barrel an angle of elevation corresponding to the distance of the mark. The second elevating device consists of the screw-

spindle G, a nut H, a pair of cone-wheels h'' i'', a shaft J, and a hand-wheel i', the object of this second elevating device being to adjust simultaneously the elevation of the gun-barrel and the rear sight. The carrier K for this second elevating device, Fig. 3, provides the connection between both elevating devices and the mount C, on which it bears through trunnions k', which permit it to partake in the swinging movements of the elevating devices when the angle of elevation is adjusted.

The first elevating device is linked to the cradle A by means of an approximately T-shaped bearing-piece M M' M'' M''', the shanks M M' of which form hollow trunnions in which are provided bearings for the shaft E. The said hollow trunnions rest in bearings N, (see also Figs. 1 and 2,) open at the bottom, secured to the cradle, and closed by bearing-plates P Q. The shank M'' of the T-shaped bearing-piece serves as a bearing-pivot for the spindle F. To the free end of the shank M'' is screwed a head m'', which, together with the part M''' connecting the shanks M M', prevent sliding of the spindle F relatively to the shank M''. The part M''' is provided with recesses for the cone-wheels e'' f''. The spindle F is provided with left-hand screw-threads and is integral with the cone-wheel f'', which meshes with the cone-wheel e'', that is non-rotatably secured on the shaft E. A shoulder on shaft E and one of the bearings for the same prevent horizontal movement of the cone-wheel e'' relatively to the shaft E.

One end of the shaft E carries the hand-wheel e', while the other end of the shaft terminates in a cone-wheel e'' that meshes with a cone-wheel t'' of a shaft T. (See also Figs. 1 and 2.) The shaft T is journaled in a casing R, inclosing the cone-wheels e'' t'', and in a projection a'' (see also Fig. 2) of the guide-piece a'' for the sight-post. The casing R is integral with the bearing-casing Q. The end of the shaft T that is opposite to the cone-wheel t'' carries a conical right-handed worm t', that meshes with the teeth d''' of the sight-post D. The pitch of the screw-threads of the spindle F and the proportion between the cone-wheels e'' f'' and e'' t'' and the worm-gear are so selected that when the hand-wheel e' is turned the sight will be adjusted through the same angle as the gun-barrel, but in the opposite direction.

The second of the two elevating devices, by means of the spindle F and the T-shaped bearing-piece M M' M² M³, is indirectly connected with the cradle A.

5 The screw G of the second elevating device carries exterior left-handed threads and its outer wall is provided with longitudinal grooves g² g³, Figs. 3 to 5, into which project the feathers k², Figs. 3 and 4, or k³, Fig. 5, secured to the carrier K. By means of the feathers k² k³ the screw G is held from rotation around its own axis, while the screw may move longitudinally relatively to the carrier K. The screw G is inclosed by the nut H, 15 that is arranged rotatably but non-slidably in the carrier K. The nut H is intergal with the cone-wheel h², with which meshes the cone-wheel i², secured on the shaft J. The shaft J carries the hand-wheel i' and is journaled in the left-hand hollow trunnion k', Fig. 3, of the carrier K and in the jack S, secured to the mount C.

The relative positions of the different parts as represented in the drawings correspond to 25 an angle of elevation of 0° and to an angle of sight of 0°.

For directing the sight-line on the target the second elevating device is made use of. When the hand-wheel i' of the second device 30 is turned counter-clockwise, the nut H will turn through the medium of the shaft J and the cone-wheels i² h². By this turning of nut H the screw G, which is prevented from rotation by feathers k² k³, will be screwed downward in said nut. This movement of screw G is simultaneously transmitted, through the medium of the spindle F and the T-shaped bearing-piece M M' M² M³, to the cradle or the gun-barrel and to the sight-post in the sense 35 that a corresponding movement of elevation takes place in the gun-barrel and the sight. The carrier K makes at the same time a slight swinging movement around the axis of its trunnions k', and the T-shaped bearing-piece 40 M M' M² M³ turns slightly around the axis of its shanks M M'. If the hand-wheel i' is turned counter-clockwise, the direction of movement of the different parts will be reversed.

45 In order to impart to the gun-barrel an elevation corresponding to the distance from the mark, the first elevating device is made use of. When the hand-wheel e' of the first device is turned counter-clockwise, the spindle F is rotated through the medium of the shaft E and the cone-wheels e² f², and the spindle F is screwed downwardly into the spindle G, that is prevented from rotation around its axis by the feathers k² k³. Through the medium of the T-shaped bearing-piece M M' M² M³ the movement of the spindle F is transmitted to the gun-barrel and the rear part of the gun-barrel is lowered. The rotation of the shaft E simultaneously causes the sight 60 to move through the same angle as the move-

ment of the gun-barrel, but in the opposite direction, through the medium of the cone-wheels e³ f³, the shaft T, and the worm-gear t⁴ d⁴. The sight-line therefore remains directed on the mark while the gun-barrel is elevated. The upper edge of the guide-piece a⁴, that partakes in the movement of the gun-barrel, indicates on the scale d³ the amount of elevation or the range corresponding to such elevation. If the hand-wheel is rotated clockwise, the rear part of the gun is elevated and the sight is moved downwardly at the same angle as that of the movement of the gun-barrel.

The two elevating devices may of course 80 be regarded as forming a single device, to the spindle F of which a sliding movement only or a sliding and rotating movement is imparted, according to the manner in which the device is operated.

Having thus described the invention, the following is what is claimed as new:

1. A sighting and elevating attachment for guns comprising a plurality of coaxially-arranged screw-spindles, a sight, means mounted independent of the screw-spindles and through which the sight is controlled, and driving means for rotating one of the screw-spindles and operating the sight-controlling means.

2. In a gun elevating and sighting attachment, means for changing the angle of elevation of the gun, means for adjusting the sight, relatively to the gun, and a driving mechanism common to both said means imparting corresponding movements thereto simultaneously in opposite directions and maintaining the sight at a substantially fixed height.

3. In a gun elevating and sighting attachment, means for changing the angle of elevation of the gun, means for adjusting the sight relatively to the gun, a driving mechanism common to both said means, and additional driving mechanism moving the gun and sight together.

4. In a gun, the combination with the gun-barrel and the rear sight, mounted to partake in the elevation of the gun-barrel, of means operating when elevation is imparted to the gun-barrel for moving the rear sight through the same angle and in the direction opposite to the movement of the gun-barrel.

5. In a gun, the combination with the gun-barrel and the rear sight, mounted to partake in the elevation of the gun-barrel, means for elevating the gun-barrel and the rear sight, and means actuated by said elevating means for moving the rear sight through the same angle and in the opposite direction to the movement of the gun-barrel.

6. In a gun, the combination with the gun-barrel and the rear sight, mounted to partake in the elevation of the gun-barrel, means for elevating the gun-barrel and the rear sight together, and means for elevating the gun-bar-

rel and the rear sight together and for simultaneously moving the rear sight through the same angle but in the opposite direction to the movement of the gun-barrel, causing the rear sight to remain stationary during the last-mentioned movements.

7. A sighting and elevating mechanism for guns, comprising a sight, means for controlling the same, an elevating mechanism embodying a bearing adapted to be trunnioned on the part to be elevated and a screw-spline turning on the bearing but held against

axial movement thereon; and driving mechanism for the screw having connection with the sight-controlling means to maintain the sight unchanged relatively to the target when the screw is rotated to adjust the gun.

The foregoing specification signed at Essen-on-the-Ruhr this 9th day of March, 1905.

OTTO LAUBER.
FRIEDRICH STOCK.

In presence of—

HARRY F. MEFFORD,
E. PFUDEL.
